UNITED STATES PATENT OFFICE

101,702

DESIGN FOR AN ELECTRIC FOOD MIXER

Ralph E. Kruck, Springfield, Mass., assignor to
Westinghouse Electric & Manufacturing Com-
pany, a corporation of Pennsylvania

Application July 31, 1936, Serial No. 64,149

Term of patent 14 years

To all whom it may concern:

Be it known that I, Ralph E. Kruck, a citizen of the United States, residing at Springfield, in the county of Hampden and State of Massachusetts, have invented a new, original, and ornamental Design for an Electric Food Mixer, of which the following is a specification, reference being had to the accompanying drawing, forming a part thereof, in which:

Figure 1 is a view in perspective, taken from the front and one side of the electric food mixer showing my new design; and

Figure 2 is an elevational view of the other side of the mixer.

I claim:

The ornamental design for an electric food mixer, substantially as shown.

RALPH E. KRUCK.
